COMBINATION CABLE CUTTING AND END SEIZING MACHINE

Robert W. Early, Norfolk, Va., assignor of forty per cent to Richard A. Holcombe, Jr., and ten per cent to Clara S. Rossen, Both of Norfolk, Va.

Application March 27, 1953, Serial No. 345,154

6 Claims. (Cl. 1—200)

This invention relates to cables, and particularly wire cables where cables are cut and the ends wrapped with marline and the like, and in particular a machine having a block with a plurality of pressure cylinders having pistons therein with the cylinders positioned perpendicular to a cable passage through the block and also in which manually actuated pumps are provided for supplying pressure to the cylinders to operate the knife for cutting a cable in said cable passage and also to operate drivers for applying wire staples, and the like on opposite sides of the point at which the cut is made.

The purpose of this invention is to provide means for seizing ends of cable, wire rope and the like which eliminates the slow laborious method of hand seizing the cable or wrapping the cable or wire rope with marline and the like.

Where cables, and particularly wire rope are cut it is necessary to wrap the ends to prevent raveling and because the cable and strands thereof are relatively stiff it is difficult to wrap the cable by hand to provide permanent seizing. With this thought in mind this invention contemplates a seizing machine including a substantially rectangularly shaped block having a cable passage extended therethrough with interchangeable dies removably mounted in the block and positioned to coact with cables extended through the passage, with staple driving and cutting blades carrying plungers slidably mounted in cylinders in the block, with manually actuated pumps positioned to pump fluid from a reservoir into the cylinders for actuating the plungers and with relief valves positioned to relieve pressure in the cylinders after the cable has been cut and seized.

The object of this invention is, therefore, to provide means for combining manually actuated seizing and cutting elements in a block whereby a cable may be cut and the ends thereof seized upon operating a lever extended from the device.

Another object of the invention is to provide a cable cutting and seizing machine that is adapted to operate on cables of different diameters.

A further object of the invention is to provide a manually actuated cable cutting and seizing machine which is of a simple and economical construction.

With these and other objects and advantages in view the invention embodies a casing, substantially rectangular shaped in cross section having a manually actuated lever pivotally mounted on the upper surface with pistons adapted to be actuated by the lever to provide pumps, with parallel cylinders having plungers therein positioned to receive fluid from the pumps, with removable dies positioned in one side of a cable passage extended through the casing, with a knife blade carried by one of the plungers for cutting the cable and with dies positioned to drive seizing clips around the cable carried by the plungers of cylinders positioned on the sides of the cylinder in which the cutting blade is positioned.

Other features and advantages of the invention will

2

appear from the following description taken in connection with the drawings, wherein:

Figure 1 is a plan view of the cable cutting and seizing machine showing a staple carrying magazine extended from one side and with parts of the magazine broken away and also with parts shown in section.

Figure 2 is a longitudinal section through the machine taken on line 2—2 of Figure 3.

Figure 3 is a sectional plan through the machine taken on line 3—3 of Figure 2.

Figure 4 is a longitudinal section through the machine taken on line 4—4 of Figure 3.

Figure 5 is a cross section through the machine taken on line 5—5 of Figure 4.

Figure 6 is a cross section through the machine taken on line 6—6 of Figure 4.

Figure 7 is a detail showing a section taken on line 7—7 of Figure 3 illustrating the staple clinching dies and showing one of the movable dies in an open position.

Figure 8 is a sectional plan, similar to that shown in Figure 3 showing the parts with the plungers in extended positions and with the plunger carrying the knife actuated through a portion of its stroke wherein the knife blade is in a position of starting the cut through the cable.

Figure 9 is a detail illustrating an end of a cable with the wire staples positioned thereon.

Figure 10 is a plan view of the end of the casing in which the cable passage is positioned with the parts in the open positions as shown in Figure 7 and with parts broken away.

Figure 11 is a detail showing a section taken on line 11—11 of Figure 8 illustrating the position of a staple before the staple is clinched over the cable.

Figure 12 is an end elevational view showing one side 35 of the machine and illustrating the position of a staple carrying magazine with parts of the magazine broken away and shown in section.

Figure 13 is a detail illustrating one of the latches for retaining the removable die carrying section of the casing 40 in operative position on the casing.

Figure 14 is a detail showing a latch for retaining a spring actuated plunger in the staple magazine in a retracted position.

Figure 15 is a detail illustrating a recess in the stem of the plunger of the staple magazine that is positioned to receive the latch shown in Figure 14.

Referring now to the drawings wherein like reference characters denote corresponding parts the improved cable cutting and seizing machine of this invention includes a casing 10 having spaced, parallel, longitudinally disposed cylinders 11, 12 and 13 therein, with staple or clip driving plungers 14 and 15 in the cylinders 11 and 13, respectively, with a plunger 16 having a cutting blade 17 therein positioned in the cylinder 12, with a fluid reservoir 18 positioned in one end, with pump cylinders 19, 20 and 21 positioned to communicate with the reservoir and cylinders 11, 12 and 13, with a cable die 22 carried by a hinged closure cap 23 and with staple carrying magazines 24 and 25 extended from the sides.

Fluid from the reservoir 18 is pumped into the cylinders in which the plungers are positioned with a hand lever 26 which extends from a yoke 27 and, as shown in Figure 1, the yoke 27 is pivotally mounted with pins 28, 29 and 30 on lugs 31, 32 and 33 which extend upwardly from the upper surface of the casing, as shown in Figure 2, the lug 31 being positioned between spaced bars 34 and 35, the lug 32 between bars 36 and 37 and the lug 33 between bars 38 and 39.

The yoke 27 of the hand lever 26 is pivotally connected by links, as indicated by the numeral 40 to connecting rods 41 of pistons 42, the upper ends of the links being pivotally mounted between the spaced bars of the

yoke with pins 43 and being connected to the connecting rods with pins 44.

As the hand lever 26 is operated fluid is drawn from the reservoir 18 through valves 45 into the cylinders 19, 20 and 21 and upon downward movement of the pistons 42 the fluid is driven through valves 46 and into the inner ends of the cylinders 11, 12 and 13.

The reservoir 18 is provided with a closure plate 47 that is secured in position with cap screws 48 and, as shown in Figure 3, the cylinders 11, 12 and 13 are provided with release passages, as indicated by the numeral 49 which are connected by a tube 50 to a relief valve 51 that is adapted to be adjusted by a thumb screw 52, as shown in Figure 2 whereby the valve may be closed by hand at the time fluid is being pumped into the cylinders and after the ends of the cable are seized and the cable cut the valve is opened by turning the screw 52 whereby pressure in the cylinders is relieved and the fluid passes back into the reservoir 18.

A bypass connection 53 is provided between the cylinder 12 and the cylinder 11 and a similar bypass connection 54 is provided between the cylinder 12 and the cylinder 13. As illustrated in Figure 6, the bypass connection 53 is provided with a slide valve 55 having an opening 56 therethrough and the valve 55 is resiliently held in a position to close the bypass with a spring 56, the tension of which is adapted to be adjusted by a plug 57. A similar slide valve 58 having an opening 59 therethrough is provided in the by-pass 54 and the valve 58 is resiliently held with a spring 60 which is held by a plug 61 which also provides means for adjusting the tension of the spring.

With the valve 51 closed pumping action of the lever 26 builds up pressure in the cylinders 11, 12 and 13, whereby the plungers are moved toward the opposite ends of the cylinders with driving dies 62 and 63 driven by a head 64 on the end of the plunger 14 and similar dies 65 and 66 driven by a head 67 carried by the plunger 15 driving staples or wire clips 68 from the magazine sections, as illustrated in Figure 8 whereby the clips are driven to arcuate grooves 69 in the die 22 so that the clips are clinched around a cable 70 extended through the machine.

As the clamping dies or drivers enter the head or closure cap 23, the blade 17 of the plunger 16 is in the position shown in Figure 8 whereby it is in engagement with the cable and at this point pressure is built up sufficiently in the cylinders 11 and 13 to move the slide valves 55 and 58 downwardly opening lower sections 71 and 72 of the bypass whereby additional fluid pumped with the continued operation of the lever 26 builds up pressure in the center cylinder 12 sufficiently to drive the cutting blade 17 through the cable with the blade entering a recess 73 in the die 22.

At this point and with the cable cut and wire clips clinched around the ends the valve 51 is opened with the thumb screw 52 whereby the pressure is relieved and the plungers are returned, the plungers 14 and 15 being returned with the springs 74 and 75 and the plunger 16 with the spring 76.

The heads 64 and 67 from which the wire clip actuating dies extend are provided with studs 77 that are threaded into openings 78 in the ends of the plungers, as shown in Figure 3. The ends of the cylinders 11 and 13 are provided with threaded collars 79 and 80 against which the ends of the springs 74 and 75 are positioned. The cylinder 12 is provided with pins 81 and 82 that extend inwardly to engage the surface of the plunger 16 whereby the pins are engaged by the end of the spring 76 to retain the spring in position.

The closure cap 23 in which the die 22 is positioned is pivotally mounted by a pin 83 and the upper part is provided with a holding plate 84 which is pivotally connected to the cap 23 with a pin 85 which extends through

hub elements 86 of the holding plate 84 and similar elements 87 of the closure cap 23.

The extended edge of the holding plate 84 is provided with spring actuated pins 88 and 89 that are resiliently held by springs 90 in caps 91 and 92, respectively, the pins being positioned to coat with lugs 93 and 94 extended from the sides of the casing 10 and having openings 95 and 96, respectively, therein to receive the inner ends of the pins 88 and 89. The edges of the holding plate 84 are provided with latched elements 97 and 98, as illustrated in Figure 13 and these elements snap over the elements 93 and 94.

The casing 10 is provided with intermediate sections 99 and 100, as illustrated in Figures 2 and 7 and the staple forming dies, such as the die 62 are positioned in recesses 101 in the intermediate sections. These sections are removable to facilitate changing the dies and holding elements to compensate for cables of different diameters. The sections 99 and 100 are provided with recesses 102 and 103 in which springs 104 and 105 which urge the drivers 62 and 63 and 65 and 66 against the heads 62 and 67 also are positioned. The springs 104 and 105 urge the intermediate sections 99 and 100 away from the body of the casing 10 to facilitate removing the intermediate sections as desired.

Staples are fed into cavities 106 and 107 in the intermediate sections 99 and 100 from magazines, such as the magazine 24 on one side and the magazine 25 on the other. Both of the magazines are the same and the same reference numerals are used for the different parts of each.

As illustrated in Figures 1 and 12 the magazine 24 is provided with a follower 110 that is positioned on the inner end of a stem 111 and the stem is urged toward staples 112 with a spring 113. The magazine is mounted 35 on the end of the intermediate sections 99 and 100 of the casing with screws 114 that are positioned in a flange 115 on the end of the magazine. The opposite end of the magazine is provided with a threaded collar 116 which forms a coupling retaining the outer section 117 in position 40 on the extended end of the magazine. The section 117 is provided with an outwardly flared flange 118 that prevents the section moving outwardly through the coupling collar 116. By this means the staples are resiliently held by the spring with the follower bearing against the staples on each side of the casing whereby with the staples secured in strips with lacquer, or the like, they are adapted to be inserted in the outer ends of the magazines 24 and 25 by removing the sections 117. The stem 111 is provided with an annular recess 119 that is positioned to receive a latch 120 for retaining the stem in the section 117 as the staples are inserted in the magazine.

As illustrated in Figures 5 and 12 the clip or staple drivers 62, 63, 65 and 66 are positioned to travel in slots, as indicated by the numeral 121, the slots being provided with enlarged sections 122 at the ends. The intermediate portion of the casing is provided with similar slots 123 to receive the cutting blade 17.

With the parts formed in this manner a cable, such as the cable 70 is extended through the dies with the machine open, as shown in Figure 7, and as the pumps are actuated with the lever 26 the plungers 14 and 15 drive staples, as indicated by the numerals 124 and 125 around the cable and as the staples are clinched the cutting blade 17 is forced through the cable dividing the cable into sections with the ends seized by the clips or staples.

The dies may be provided in different sizes to correspond with cables of different diameters and with the dies interchangeable the machine may readily be adjusted to cut and seize cables of different sizes.

It will be understood that modifications, within the scope of the appended claims, may be made in the design and arrangement of the parts without departing from the spirit of the invention.

What is claimed is:

1. In a cable cutting machine, the combination which

comprises a casing having a cable receiving opening extended therethrough, a knife positioned to cut a cable extended through said opening, a centrally positioned plunger for operating the knife, plungers spaced from the centrally positioned plunger for driving clips around the cable in the cable opening, manually actuated pumps provided in the casing and positioned to pump fluid under pressure for operating the plungers, and means for relieving the pressure to release the plungers.

2. In a cable cutting machine, the combination which comprises a casing having a cable receiving opening extended therethrough, a knife positioned to cut a cable extended through said opening, a centrally positioned plunger for operating the knife, plungers spaced from the centrally positioned plunger for driving clips around the cable in the cable opening, manually actuated pumps provided in the casing and positioned to pump fluid under pressure for operating the plungers, means for relieving the pressure to release the plungers, and means for feeding clips into the casing.

3. In a cable cutting machine, the combination which comprises a casing having a plurality of cylinders and a reservoir therein and having a cable receiving opening extended through one end, dies in said cable receiving opening of the casing, a cutter in the casing and positioned to cut a cable in said dies, clip drivers also positioned in the casing, plungers slidably mounted in the cylinders of the casing and said cylinders positioned whereby plungers therein actuate the clip drivers and cutter, and manually actuated pumps in the casing positioned to pump fluid from the reservoir to the cylinders for actuating the clip drivers and cutter.

4. In a cable cutting machine, the combination which comprises a casing having a plurality of cylinders and a reservoir therein and having a cable receiving opening extended through one end, dies in said cable receiving opening of the casing, a cutter in the casing and positioned to cut a cable in said dies, clip drivers also positioned in the casing, plungers slidably mounted in the cylinders of the casing and said cylinders positioned whereby plungers therein actuate the clip drivers and cutter, manually actuated pumps in the casing positioned to pump fluid from the reservoir to the cylinders for actuating the clip drivers and cutter, and manually actuated means for releasing pressure of the cylinders.

5. In a cable cutting machine, the combination which

comprises a casing having a plurality of cylinders and a reservoir therein and having a cable receiving opening extended through one end, dies in said cable receiving opening of the casing, a cutter in the casing and positioned to cut a cable in said dies, clip drivers also positioned in the casing, plungers slidably mounted in the cylinders of the casing and said cylinders positioned whereby plungers therein actuate the clip drivers and cutter, manually actuated pumps in the casing positioned to pump fluid from the reservoir to the cylinders for actuating the clip drivers and cutter, manually actuated means for releasing pressure of the cylinder, said casing having bypass connections between the cylinder and valves in said bypass connections.

6. In a cable cutting and seizing machine, the combination which comprises a casing having a transversely disposed cable passage extended through one end with spaced parallel cylinders extended from one side of said passage and positioned perpendicularly to the axis of said cable passage, plungers slidably mounted in said cylinders, a cable cutting knife carried by one of said plungers and positioned to cut a cable in said cable passage, clip drivers carried by plungers positioned on opposite sides of said knife carrying plunger, a clip clinching die mounted in the casing and positioned on the side of the cable passage opposite to that from which the cylinders extend, said casing having a hinged section in which said clinching die is positioned, a holding plate hinged to the section in which the forming die is positioned and adapted to be secured to the casing for retaining the parts in assembled relation, resilient means on the plungers for urging the plungers away from the cable passage through the casing and manually actuated hydraulic means for supplying fluid under pressure to said cylinders.
